O. J. JOHANSON

NAIL DRIVER

Filed Nov. 6, 1922

Inventor.
Olof J. Johanson
by Heard Smith & Tennant.
Atty's.

UNITED STATES PATENT OFFICE.

OLOF J. JOHANSON, OF BOSTON, MASSACHUSETTS.

NAIL DRIVER.

Application filed November 6, 1922. Serial No. 599,270.

To all whom it may concern:

Be it known that I, OLOF J. JOHANSON, a subject of the King of Sweden, and resident of Boston, county of Suffolk, State of Massachusetts, have invented an Improvement in Nail Drivers, of which the following description, in connection with the accompanying drawing, is a specification, like characters on the drawing representing like parts.

This invention relates to implements for driving nails and has for some of its objects to provide a hand implement for this purpose which embodies novel means for transferring the nails from the reservoir to the chute by which they are conducted to the driving element and also to provide a novel construction by which after the driver has begun its nail-driving movement it can be returned to normal position until after completing such movement thus insuring that each nail will be completely driven.

My device comprises the usual frame having a driving element, a chute for conducting the nails thereto, a nail reservoir, and means for transferring the nails from the reservoir to the chute. The means employed for this purpose is a magnetic element constructed so that it can be moved into position so that one or more nails from the reservoir will be attracted thereto, and may also be moved into position to deliver the nails to the chute. The nails are dislodged from the magnetic element by delivering to the latter a blow of sufficient force to jar the nails loose therefrom. This blow is herein delivered by providing an abutment against which the magnetic element strikes during its movement.

In order to give an understanding of the invention I have illustrated in the drawings a selected embodiment thereof which will now be described after which the novel features will be pointed out in the appended claims.

Fig. 1 is a vertical sectional view through a nail driver embodying my invention.

Fig. 2 is a detail view showing the means for controlling the driver.

The device herein shown comprises a suitable frame 1 having a handle 2 by which it may be manipulated and moved over the surface 3 into which the nails are to be driven. The embodiment of the invention herein shown is specially designed for nail-

ing flooring in place but I wish it understood that the invention is adapted for various other purposes and is not confined to any particular nailing operation.

The driving element by which the nails are driven comprises a driver 4 which is secured to a plunger 5 that operates in a guiding sleeve 6 supported at one end of the frame. This driver is normally held in raised position shown in Fig. 1 by means of a spring 7 which encircles the shank 5 and bears at one end against a shoulder 8 formed on the shank and at the other end against a tubular member 9 situated within the sleeve 6. Situated beneath the driver 4 is a guiding member 10 which is herein shown as adapted to rest on the surface 3 and which thereby forms a support for the frame, and which is also provided with a nail-delivery passage 11 situated directly in line with the driver 4 and through which the nails 12 are driven. The upper end of the shank 5 is provided with a handle or knob 13 by which the driver may be manually depressed.

The nails 12 are delivered to the driver through the medium of a chute 14 that may have any suitable or usual construction, said chute having the usual nail-receiving slot 15 through which the nails depend, thereby holding said nails in upright position.

The guiding member 10 is shown as having a positioning spring 16 associated therewith, which forms a stop for the end nail 12 and thus holds said nail in position to be acted upon by the driver 4. This spring is shaped to engage underneath the head of the nail and thus hold the nail suspended until said nail is engaged by the driver. The spring 16 yields as the driver descends thus allowing the nail to pass downwardly through the passageway 11.

17 indicates a reservoir to contain nails, such reservoir having a cover 18 through which the nails may be deposited therein.

For transferring the nails from the reservoir 17 to the chute 14 I have provided a magnetic element 19 which is movably mounted and is adapted to be carried into a position in which the nails in the reservoir 17 will be attracted thereto and is also adapted to be carried into a position to deliver such nails into the upper end of the chute 14.

In the construction herein shown this magnetic element is mounted on an arm 20

that is pivoted to the frame at 21, said arm operating through a slot 22 formed in the housing for the reservoir 17.

Means are provided for manually moving 5 the magnetic element 19 whenever it is desired to reload the chute and while various devices for this purpose may be employed that herein illustrated is regarded as being entirely satisfactory. The arm 20 is pivot- 10 ally mounted by being made fast on a rock shaft 21 and the latter has fast thereto an arm 23 which is connected by a link 24 to one arm 25 of an elbow lever pivoted to the frame at 26, the other arm 27 of said 15 elbow lever being connected by a link 28 to one end 29 of a trigger or finger piece 30 which in turn is pivoted to the frame at 31. The arm 20 is acted upon by a spring 32 which tends to hold the magnetic element 20 in retracted position shown in full lines in which position it rests against an abutment or stop 33. When the finger piece 30 is raised into the dotted line position Fig. 1 it operates through the link and lever con- 25 nection to swing the magnetic element into the dotted line position thus bringing it into the reservoir 17. When in this position it will attract one or more nails to it by its magnetic attraction. When the trigger is 30 released the spring 32 will swing the magnetic member back into the full line position Fig. 1 and said member will carry with it the nails which have been attracted thereto.

35 The strength of the spring 32 is such that it will bring the magnetic element against the stop 33 with a hammer-like blow and this blow will be sufficient to dislodge from said magnetic element the nails which are 40 magnetically held thereto, such nails falling into the upper end of the chute as indicated in the drawings.

The chute 14 is of the usual shape so that 45 nails which fall into it will naturally drop into a position where they will depend through the slot 15 as shown. The loading of the chute, therefore, involves the act of raising the finger lever 30 and then releasing it and this may be done one or more times as necessary to deliver the desired 50 number of nails into the chute.

The finger piece 30 is situated beneath 55 the handle 2 and is thus in convenient position to be manipulated by the fore finger of the operator.

An important feature of this invention is the construction by which the magnetic element with the nails adhering thereto is brought up against the stop or rest 33 with 60 a hammer-like blow thereby jarring the nails from said element.

While I have herein shown a construction 65 which the blow which jars the nails from the magnetic element is secured by driving said element against a fixed stop

yet the invention is not necessarily limited to such construction as the blow for dislodging the nails from the magnetic element may be derived by some other means.

Another feature of the invention relates 70 to the means for controlling the driver whereby after the driver has once been started on its nail-driving movement it cannot be returned to its raised position until it has completed such nail-driving movement.

The plunger 5 is provided with a pin or projection 34 which operates in a slot 35 formed in the sleeve 6. This slot is provided with serrated edges 36 and at the top 80 and bottom it is widened as shown at 37. The pin 34 carries a spring member 38 which is slightly longer than the width of the slot between the serrated walls but is shorter than the widened portions 37 of the slot. When the driver is in its elevated position the spring member 38 occupies the widened upper end of the slot as shown in Fig. 2. As the driver starts downwardly 85 said member is carried into the narrower portion of the slot having the serrated edges 36 and as it passes into said portion of the slot the ends of the spring are bent backwardly or upwardly, as shown by dotted lines Fig. 2. This spring when in this position functions as a ratchet to prevent return movement of the plunger 5, said spring, however, permitting continued downward movement. When the plunger has completed its downward stroke the spring passes 90 into the lower widened end 37 of the slot and when in this position it resumes its straight shape. The plunger may then be elevated and as it rises the ends of the spring element will be bent downwardly and will 95 function as a ratchet to prevent downward movement of the plunger while permitting continued upward movement thereof.

With this device, therefore, the direction 100 of the movement of the plunger can only be reversed when the plunger is at either end of its stroke and, therefore, if during one driving operation any nail is not completely driven the plunger will remain in 105 depressed position and cannot be raised until it is given another blow to drive it to the lower limit of its movement. Such added blow will complete the driving of the nail and thus with this arrangement the 110 complete driving of every nail is insured.

While I have illustrated herein a selected 115 embodiment of my invention I do not wish to be limited to the constructional features shown.

I claim:

1. In a nail-driving implement, the combination with a driving element, of a reservoir, a nail chute leading to the driving element and means for transferring nails from the reservoir to the chute, said means com- 120

prising a magnetic element, means to move said element into position to take nails from the reservoir by magnetic attraction, and means to give said element a blow sufficient 5 to dislodge the nails therefrom.

2. In a nail driver, the combination with a driving element, of a reservoir, a nail chute leading to the driving element and means for transferring nails from the reservoir to the chute, said means comprising a magnetic element, means to move said element into position to take nails from the reservoir by magnetic attraction and then to move said element into the chute, and a 10 stop for arresting suddenly the movement of the magnetic element thereby to dislodge the nails therefrom.

3. In a nail driver, the combination with a driving element, of a reservoir, a nail chute leading to the driving element and means for transferring nails from the reservoir to the chute, said means comprising a pivotally-mounted magnetic element, means for moving said element into position to take 25 nails from the reservoir by magnetic at-

traction, a spring to retract said element, and a stop to arrest suddenly the retracting movement of said element whereby the nails will be jarred therefrom.

4. In a nail driver, the combination with a guiding sleeve, of a plunger operating therein, a driver carried by the plunger, said sleeve having a slot which presents widened ends, a projection extending from said plunger and operating in the slot and a spring ratchet member carried by the projection and located in said slot, said spring member having a greater length than the width of the slot but less length than the widened ends of the slot, whereby as the spring member is carried into the narrow portion of the slot by the downward movement of the plunger the ends of the spring are bent backwardly and thereby locking the plunger against upward movement until the plunger has completed its downward movement.

In testimony whereof, I have signed my name to this specification.

OLOF J. JOHANSON.
